UNITED STATES PATENT OFFICE

141,020

DESIGN FOR A CIGARETTE DISPENSER OR THE LIKE

Edward Erger, Los Angeles, Calif., assignor to Robert S. Herman, Los Angeles, Calif.

Application December 1, 1944, Serial No. 116,661

Term of patent 3½ years

(Cl. D85—2)

To all whom it may concern:

Be it known that I, Edward Erger, a citizen of the United States, residing at Los Angeles, in the county of Los Angeles and State of California, have invented a new, original, and ornamental Design for a Cigarette Dispenser or the Like, of which the following is a specification, reference being had to the accompanying drawing, forming a part thereof.

Fig. 1 is a front perspective view of a cigarette dispenser showing my new design;

Fig. 2 is a view similar to Fig. 1 but showing the dispenser in open position;

I claim:

The ornamental design for a cigarette dispenser or the like, as shown.

EDWARD ERGER.
